UNITED STATES PATENT OFFICE.

FREDERICK H. HILL, OF LOS ANGELES, CALIFORNIA, ASSIGNOR TO MONOGRAM SHOP,
A PARTNERSHIP CONSISTING OF FREDERICK H. HILL AND CYRIL FREEDMAN,
BOTH OF LOS ANGELES, CALIFORNIA.

DESIGN FOR A RING.

Application filed March 20, 1929. Serial No. 30,543. Term of patent 14 years.

To all whom it may concern:

Be it known that I, FREDERICK H. HILL, a citizen of the United States, residing at Los Angeles, county of Los Angeles, State of California, have invented a new, original, and ornamental Design for Rings, of which the following is a specification, reference being had to the accompanying drawing, forming part thereof.

Figure 1 is a side elevation of a ring showing my new design, and

Figure 2 is a plan view of the same, and

Figure 3 is a sectional view with parts shown in elevation.

I claim:

The ornamental design for a ring as shown.
